UNITED STATES PATENT OFFICE.

ELVIN B. BABCOCK, OF SEATTLE, WASHINGTON.

GAS-BURNER.

1,101,233.

Specification of Letters Patent. Patented June 23, 1914.

Application filed September 20, 1913. Serial No. 790,881.

To all whom it may concern:

Be it known that I, ELVIN B. BABCOCK, a citizen of the United States, residing at Seattle, in the county of King and State 5 of Washington, have invented certain new and useful Improvements in Gas-Burners, of which the following is a specification.

This invention relates to improvements in gas burners of the class used in cooking and 10 heating stoves, ranges and furnaces.

The object of my improvements is to produce a burner of this type of durable and inexpensive construction, economical in the consumption of gas, and which may be adjusted to apply heat in a most efficient manner.

The invention consists in the novel construction and adaptation of devices herein-after described with reference to the accompanying drawings, and finally pointed out 20 particularly in the claims—the features of which I have invented.

In the drawings, Figure 1 is a longitudinal section of a gas burner embodying the 25 present invention; and Fig. 2 is a sectional view illustrating the invention applied to a cooking range.

The reference numeral 5 designates the tubular body portion of the burner having a 30 closed end at 6 and one or more side outlets, as at 7. At the closed end is a chamber 8 of greater diameter than the internal diameter of the body to afford a cushion space which serves to equalize the delivery 35 of the combustible gases from said outlets.

The outlets are formed in branches 9 having their axes disposed in a plane extending radially, or nearly so, from the axis of the body. Each of said branches is formed 40 with an enlargement near its outer end to provide within the branch a cavity 10 of greater diameter than at the throat 11 or its outlet or orifice 7. By thus enlarging the branches near their outlets, the gases delivered therefrom are consumed in a hotter 45 flame and closer to the orifices than where the branches are of equal diameters throughout or where they taper gradually to the orifices. At any rate, there is an apparent 50 improvement in the heating efficiency of the flames produced from the bulbular type of burner nozzle over the ordinary forms. The body 5 extends through an opening 12 in the wall 13 of the fire-box of a stove and 55 externally of the latter the body terminates

in a flaring attachment 14 which affords a funnel-shaped mixing chamber. Axially of said attachment and connected integrally therewith by arms 15 is a hub 16 provided with a threaded hole in which is screwed the 60 nozzle 17 of a gas supply pipe 18. A damper plate 19 provided with a centrally threaded hole to engage the threads of the nozzle is screwed upon the latter to or from the mouth of the mixer 14 for regulating 65 the effective size of the opening for the admission of air thereinto.

20 represents a collar secured to the burner, as by a set screw 21, and is provided with an arm 22 which is utilized to 70 impart rotary adjustment to the burner.

The burner is mounted upon the nozzle 17 to afford rotary movement for directing the burner orifices and, by the provision of the screw-threads within the hub, the burner 75 may be moved in an axial direction to cause the nozzle to extend more or less into the mixer.

The operation of the invention may be best explained in its application to a stove 80 such as illustrated in Fig. 2. As shown, said stove is provided at its front with a compartment 24 which communicates with a combustion chamber 25 extending between the oven 26 and the stove-top 27. The chamber 25 is connected at the rear with a diving-flue 28 which is connected by a horizontal flue 29 below the oven with a rising-flue 30 which communicates by a flue 31 with the smoke-pipe connection 32. A damper 33 is 85 provided for an opening 34 between chamber 25 and the flue 31, and 35 is a damper for regulating the flow of the combustion gases from the chamber 25 into the diving-flue 28. 90

36 represents a water-heating coil located in the compartment 24.

Referring to Fig. 2, when the dampers 33 and 35 are in the positions shown and the burner is in the rotary position denoted by 100 the full lines in the view, to have the burner branches directed horizontally, the flames and hot gases derived from the combustible gases emitted therefrom will take the course indicated by full line arrows, that is to say—through the chamber 25 and thence by the various flues to escape through the pipe connection 32. When the damper 35 is closed and the other one, 33, opened, the 105 flow will be from the chamber 25 directly 110

into the pipe connection. Under the first arrangement the top of the stove and the oven are both subjected to the heat and in the other case the oven is cut out, so to speak, 5 and the heat is utilized for cooking on the stove top only. When, however, the burner is turned by means of handle 22 (Fig. 1) to point the branches downwardly, as indicated by broken lines 9¹, (Fig. 2), then the 10 flames from the burner will be accordingly directed against the water-heating coil 36 before entering the chamber 25. Moreover, the burner may be turned into other rotary positions to apply the flames, for example, 15 more directly against the top of the oven or against the underside of the stove-top as may be determined by the attendant.

What I claim, is—

1. A gas-burner having a body portion 20 with a cushion chamber at one end and a mixing chamber at its other end, an outlet branch for said body and formed internally with an annular recess in proximity to the outer end of the branch, and a gas supply 25 nozzle extending axially into said mixing chamber.

2. A gas-burner comprising a mixing chamber, a tubular body connected in axial alignment therewith and having an imperforated end remote from said chamber, outlet branches provided for said body and each formed with a cavity of greater diameter than both the orifice of the branch and the throat which connects the cavity with 35 the interior of said body, and a gas supply nozzle extending axially into said mixing chamber.

3. The combination with a stove, of a burner extending into said stove, said burner 40 being provided with a mixing chamber at the end outside of the stove and an enlarged cushioning chamber at the opposite end thereof within the stove, and radially disposed bulbular discharge orifices positioned 45 intermediate of said end portions and within the stove, said burner being supported entirely at its forward end and being provided with means whereby it may be rotated to adjust the positions of said bulbular dis-

charge orifices to any desired angle within 50 the stove.

4. In an attachment of the class described, a tubular burner, a gas inlet pipe having adjustably mounted thereon a damper plate and a mixing chamber adapted to receive 55 said tubular burner, said tubular burner being provided with an enlarged integral annular cushioning chamber and a plurality of bulbular burner nozzles intermediate of the ends of said tubular burner and integral 60 therewith.

5. The combination with a stove, of a tubular burner provided with means to adjust the same with relation to the stove, said tubular burner having at one end thereof a cushioning chamber, and a plurality of 65 radial bulbular burner nozzles intermediate of its ends, said burner nozzles being each provided with a throat or outlet port and an annular cavity intermediate of the throat 70 and outlet port thereof, said outlet port being smaller in diameter than either the throat or the annular cavity.

6. In an attachment of the class described, a tubular burner having an enlarged chamber at one end thereof and provided intermediate of its ends with a plurality of integral bulbular burner nozzles, said burner nozzles being of a height which is less than 75 the diameter of said tubular burner.

7. In combination with a stove, a gas inlet, of a tubular burner revolvably mounted on said gas inlet and having an enlarged end portion and a plurality of radially disposed bulbular burner nozzles, said burner 85 nozzles having their axes disposed in the same plane with said tubular burner, and means whereby the direction of the heat passing from said bulbular burner nozzles may be changed by rotating said tubular 90 burner upon said gas inlet.

Signed at Seattle, Wash., this 13th day of September, 1913.

ELVIN B. BABCOCK.
